DESIGN FOR A COMBINATION PHOTOGRAPHIC FILTER TURRET AND SUN-SHADE

Alex J. Weinstein, Mount Vernon, N. Y.

Application February 27, 1948, Serial No. 144,766

Term of patent 14 years

(Cl. D61—1)

To all whom it may concern:

Be it known that I, Alex J. Weinstein, a citizen of the United States, a resident of Mount Vernon, New York, have invented a new, original, and ornamental Design for a Combination Photographic Filter Turret and Sunshade, of which the following is a specification, reference being had to the accompanying drawing, forming a part thereof.

Fig. 1 is a horizontal side view of a design for a combination photographic filter turret and sunshade, showing my new design;

Fig. 2 is a rear view thereof;

Fig. 3 is a vertical side view thereof; and

Fig. 4 is a front view thereof.

I claim:

The ornamental design for a combination photographic filter turret and sunshade, as shown.

ALEX J. WEINSTEIN.
